TRIPLE DRESSER

Jan Lunde Knudsen, Boston, Mass., assignor to Heywood-Wakefield Company, Gardner, Mass., a corporation of Massachusetts

Filed Aug. 24, 1959, Ser. No. 57,259

Term of patent 7 years

(Cl. D33—6)

FIG. 1.

FIG. 2.

FIG. 3.

FIG. 4.

The essential features of the design are shown in solid lines. The end not shown is like the end shown while the back is conventionally plain.

We claim:

The ornamental design for a cabinet, as shown and described.

UNITED STATES PATENT OFFICE
CERTIFICATION OF CORRECTION

Design No. 189,041

October 18, 1960

Jan Lunde Knudsen

It is hereby certified that error appears in the above numbered patent requiring correction and that the said Letters Patent should read as corrected below.

Column 1, line 1, beginning with "Figure 1", strike out all to and including "and described." in lines 8 and 9, and insert instead the following:

Fig. 1 is a front perspective view of a triple dresser showing my new design;

Fig. 2 is a view of one of the drawers as seen in elevation from the front, but on a scale larger than Fig. 1;

Fig. 3, is a fragmentary sectional detail view on the line 3-3 of Fig. 2; and

Fig. 4 is a fragmentary sectional detail view on the line 4-4 of Fig. 1.

I claim:

The ornamental design for a triple dresser substantially as shown and described.

Column 2, line 2, beginning with "UNITED STATES PATENTS", strike out all to and including "table-cabinet combination." in line 10, and insert instead the following:
